UNITED STATES PATENT OFFICE.

HARRY SIDNEY BAYLES, OF LONG ISLAND, NEW YORK.

SCREEN.

1,035,519.

Specification of Letters Patent. Patented Aug. 13, 1912.

Application filed December 28, 1911. Serial No. 668,347.

To all whom it may concern:

Be it known that I, HARRY SIDNEY BAYLES, a citizen of the United States, residing at Long Island, in the county of Nassau and State of New York, have invented certain new and useful Improvements in Screens, of which the following is a specification, reference being had to the accompanying drawings.

10 This invention relates to new and useful improvements in window screens and more particularly to an adjustable screen, and my object is to provide a device of this character with improved means for retaining the sections of the screen together.

15 A further object of the invention resides in providing improved slides which are secured to upper and lower bars of the frames of the screen sections, which slides are 20 adopted to interlock with one another, and a still further object resides in providing means to prevent the entrance of insects between the screening material of the one section of the device and the end bar of the 25 opposite section thereof.

20 A still further object resides in providing a device which is extremely simple and durable in construction, inexpensive to manufacture, and one which is very efficient and 30 useful in operation.

With these and other objects in view, my invention consists in the novel features of construction, combination and arrangement of parts as will be hereinafter referred to 35 and more particularly pointed out in the specification and claims.

In the accompanying drawing forming a part of this application, Figure 1 is a perspective view of the device. Fig. 2 is a 40 vertical section through the two sections of the screen. Fig. 3 is a horizontal section therethrough, and, Fig. 4 is an enlarged section through the interlocking slides used on the respective sections of the screen.

45 In carrying out my invention, I shall refer to the drawing in which similar reference characters designate corresponding parts throughout the several views and in which 1 and 2 indicate the rectangular frame sections of an adjustable screen, said sections being formed of the wood bars or strips 3 covered with a metallic facing 4, and a screening material 5, is held on the sections 1 and 2 between the wood bars or strips 3 50 and the metallic covering 4 thereof. The sections 1 and 2 are slidably secured to one

another by being, respectively, provided with the interlocking members 6 and 7, said interlocking members being disposed on the upper and lower bars of the inner opposed faces of said sections. The members 6 on the section 1 which form one portion of the interlocking members of the device, comprise strips which are soldered, welded, riveted or otherwise secured to the section 60 and have their side edges bent inwardly toward one another and soldered together at the point 8 along the longitudinal center of said strips, while the remaining portions thereof are flared outwardly beyond this point 8 to form the tongues 9, the extreme free ends of said tongue portions 9 being bent under the lower face thereof, as shown at 65 10. As stated, the side edges of each of the members 6 are bent inwardly toward one another and the portions forming the side edges of the strip after being so disposed, are bulged or raised the full length thereof to form ridges, as shown at 11, while the inwardly bent portions between the ridges 70 11 and the point 8 at which said bent portions are soldered, are engaged with the base portion of the strip 6 and soldered or otherwise secured thereto. The ridges 11 extend a slight distance beyond the ends 10 of the 75 flared portions 9, and between these two portions are inclosed channel-ways 12, it being understood that the flared portions 9 have 80 somewhat of a spring tension.

As stated, there are two of these members, one on the upper strip or bar of the frame 1 and another on the lower strip thereof, and engaged with these members are the members 7 on the section 2, said latter members comprising strips which are 90 soldered, welded, riveted or otherwise secured to the upper and lower bars of that frame, the same having their side edges bent inwardly toward one another, as shown at 95 13, and engaged between the ridges 11 and the bent ends 10 on the flared portions 9 of the members 6. The ends 13 of the members 7 being engaged in this manner between the portions 10 and 11, will securely retain the 100 sections of the screen in sliding engagement with one another and the spring tension of the portions 9 will not only hold the sections of the screen in any adjusted position, but will permit of a ready movement of the sections with respect to one another. These 105 interlocking members 6 and 7 extend for the greater portion of the length of the upper 110

and lower bars of the frame sections, and in order to limit the movement of said frame sections so as to prevent the total disengagement of said sections with one another, I provide the opposite end bars of the sections with the vertical but laterally extending strips 14 and 15, respectively, said strips being formed from the metal covering or facing 4 thereon. From this construction, it will be seen that when extended to the maximum degree, the strips 14 and 15 will contact with one another to limit the movement of the sections, while when disposed to the maximum degree in the opposite direction, said strips will contact with the metallic facing 4 on the end bars of the opposite sections to prevent any further movement thereof. These laterally extending strips 14 and 15 are of such a width as to contact with the screening material of the opposite section, and thus, it will also be seen that the same will prevent any possible entrance of flies or other insects between the end bars of one section and the screening material of the other.

From the foregoing, it will be seen that I have provided an adjustable screen, the sections of which are provided with interlocking members on the upper and lower bars thereof, which interlocking members are of improved form, and it will still further be seen that these interlocking members are of such a character as to securely retain the sections together and in any adjusted position with respect to one another, at the same time permitting of a smooth and ready movement. Furthermore, it will be seen that I have provided means to prevent the entrance of insects in the space between the screening material of one section and the screening material of the opposed section, which means comprises laterally extending strips on the metallic covering or facing of the end bars of the respective sections. It will further be seen that my device is one of extremely simple and durable construction, inexpensive to manufacture, and one which is very efficient and useful in operation.

Having thus described my invention, what I claim is:—

1. An adjustable screen, comprising a pair of frame sections, and interlocking members thereon, comprising strips on one of said

sections, the side edges of which are bent inwardly and thence outwardly to form spring portions thereon, and additional strips carried on the opposed section having the side edges thereof bent somewhat inwardly to engage between the spring portions and base portions of the opposed strips.

2. An adjustable screen, comprising a pair of frame sections, and interlocking slides thereon, comprising strips on one of said sections, the side edges of which are bent inwardly toward one another to meet at the longitudinal centers of said strips, the remaining portions of said inwardly bent side edges being flared outwardly from one another to form spring portions, and additional strips carried on the opposed frame sections, said latter strips having the side edges thereof bent inwardly toward one another to engage the side edges of the spring portions.

3. An adjustable screen, comprising frame sections and interlocking slides thereon, comprising strips secured to one of said sections having the side edges thereof bent inwardly toward one another to meet at the longitudinal centers of said strips, the remaining portions of said inwardly bent portions beyond the meeting point being flared outwardly to form spring portions thereon, the side edges of the base portions of the strips after having been so bent, being bulged to form ridges, and additional strips secured to the opposed frame section, said latter strips having the side edges thereof bent inwardly in binding engagement between the side edges of the spring portions and the ridges of the opposed strips.

4. An adjustable screen, of the class described, comprising a pair of frame sections, the bars of which are covered with a metal facing, the opposite end bars of said frame sections having the metal facing thereon, provided with oppositely disposed lateral strips, and interlocking slide members on said frame sections.

In testimony whereof I hereunto affix my signature in the presence of two witnesses.

HARRY SIDNEY BAYLES.
